WALL FLANGE FOR SHOWER CURTAIN ROD

Herbert H. Wessel, Haverford Township, Delaware County, Pa., assignor to Wessel Hardware Corporation, Philadelphia, Pa., a corporation of Pennsylvania

Filed Mar. 6, 1963, Ser. No. 73,837

Term of patent 14 years

(Cl. D21—1)

FIG. 1 is a perspective view of a wall flange for shower curtain rod showing my new design;

FIG. 2 is a front elevational view thereof;

FIG. 3 is a rear elevational view thereof;

FIG. 4 is a side elevational view thereof;

FIG. 5 is a top plan view thereof; and

FIG. 6 is a bottom plan view thereof.

The design is characterized by the backing plate and boss being integral and the outline of the exterior surface of the boss being repeated by the configuration of the backing plate.

I claim:

The ornamental design for a wall flange for shower curtain rod, substantially as shown and described.
